US00D859398S

(12) **United States Design Patent** (10) Patent No.: **US D859,398 S**
(45) Date of Patent: **** Sep. 10, 2019**

(54) **ELECTRONIC DEVICE**(71) Applicant: **Apple Inc.**, Cupertino, CA (US)(72) Inventors: **Jody Akana**, San Francisco, CA (US); **Bartley K. Andre**, Palo Alto, CA (US); **Shota Aoyagi**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Mikael Silvanto**, San Francisco, CA (US); **Christopher J. Stringer**, Woodside, CA (US); **Eugene Antony Whang**, San Francisco, CA (US); **Rico Zörkendorfer**, San Francisco, CA (US)(73) Assignee: **Apple Inc.**, Cupertino, CA (US)(***) Term: **15 Years**(21) Appl. No.: **29/608,814**(22) Filed: **Jun. 26, 2017****Related U.S. Application Data**

(63) Continuation of application No. 29/548,706, filed on Dec. 16, 2015, now Pat. No. Des. 790,535, which is a continuation of application No. 29/466,556, filed on Sep. 9, 2013, now abandoned.

CLAIM

The ornamental design for an electronic device, as shown and described.

drawing(s)/photograph(s) will be provided by the Office upon request and payment of the necessary fee.

FIG. 1 is a bottom front perspective view of an electronic device showing the claimed design;

FIG. 2 is a bottom rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is an enlarged view of a portion of FIG. 4;

FIG. 10 is a bottom front perspective view of an electronic device showing another embodiment of the claimed design;

FIG. 11 is a bottom rear perspective view thereof;

FIG. 12 is a front view thereof;

FIG. 13 is a rear view thereof;

FIG. 14 is a top view thereof;

FIG. 15 is a bottom view thereof;

FIG. 16 is a left side view thereof;

FIG. 17 is a right side view thereof; and,

FIG. 18 is an enlarged view of a portion of FIG. 13.

The dashed broken lines in the figures show portions of the electronic device that form no part of the claimed design.

The dot-dash broken lines in the figures show unclaimed boundaries that form no part of the claimed design.

The dot-dot-dash broken lines in the figures and the masked areas within the dot-dot-dash lines show portions of the electronic device that form no part of the claimed design.

CERTIFICATE OF CORRECTION

PATENT NO. : D859,398 S
APPLICATION NO. : 29/608814
DATED : September 10, 2019
INVENTOR(S) : Akana et al.

Page 1 of 1

It is certified that error appears in the above-identified patent and that said Letters Patent is hereby corrected as shown below:

On the Title Page

Page 3, please replace the 20th paragraph of the DESCRIPTION section with the following paragraph:
“The dashed broken lines in the figures show portions of the electronic device that form no part of the claimed design. The dot-dash broken lines in the figures show boundaries that form no part of the claimed design.”

Signed and Sealed this
Tenth Day of December, 2019

Andrei Iancu
Director of the United States Patent and Trademark Office
